LIP AND FACIAL ROUGE COMPACT

Filed Aug. 31, 1938

INVENTOR,
GEORGE A. WILLIAMS
BY Martin O. Smith, ATTY.

UNITED STATES PATENT OFFICE

2,219,000

LIP AND FACIAL ROUGE COMPACT

George A. Williams, Los Angeles, Calif.

Application August 31, 1938, Serial No. 227,674

1 Claim. (CL 132—79)

My invention relates to a cosmetic compact and more particularly to a small container that may be conveniently carried in a purse or handbag and the principal object of my invention is, 5 to provide a compact having containers for lip rouge and facial rouge, together with a member provided on its ends with applicators that are utilized for transferring the rouge from the containers of the compact to the lips and cheeks 10 of the user.

A further object of my invention is, to provide a compact of the character referred to having a body, on the ends of which are removably positioned thimble-like caps, one of which contains a 15 rouge especially applicable for the lips and the other containing facial rouge and a member arranged for longitudinal sliding movement through the body of the device, said member carrying on its ends small swab-like applicators of soft material that may be conveniently used for transferring the rouge from the containers to the lips 20 and face.

With the foregoing and other objects in view, my invention consists in certain novel features 25 of construction and arrangement of parts that will be hereinafter more fully described and claimed and illustrated in the accompanying drawing in which:

Fig. 1 is a perspective view of a compact constructed in accordance with my invention.

Fig. 2 is a longitudinal section taken on the line 2—2 of Fig. 1.

Fig. 3 is a vertical longitudinal section taken through the central and one end portion of the 35 compact and showing one of the applicators moved into position where it makes contact with the rouge carried in one of the end caps.

Fig. 4 is a perspective view of the central and end portion of the compact with the sliding member moved to its limit of movement in one 40 direction for use in applying rouge to the lips or face.

Referring by numerals to the accompanying drawing which illustrates a preferred embodiment 45 of my invention, 10 designates the main body of the compact which may be formed of any suitable material, but preferably of hardened plastic material such as Bakelite, Catalin, Celluloid, or the like. This body 10 is preferably cylindrical in 50 form and has its end portions reduced in diameter so as to form short cylindrical lugs 11.

Formed axially through the body 10 and lugs 11 is a bore 12 and formed in the body 10 is a longitudinally disposed slot 13 that communicates with 55 the intermediate portion of the bore 12.

Removably positioned on the lugs 11 that project from the ends of the body 10 are thimble-like caps 14, each of which contains a body of rouge R. One of these bodies of rouge is of the particular type applicable for use on the lips while 5 the other body is of the type particularly applicable for use on the cheeks.

Arranged to slide freely through the bore 12 is a pencil-like member 15 and seated in the central portion thereof is the threaded end of a shank 16 10 that projects through slot 13 and the outer end of said shank carrying a button-like head 17.

The ends of sliding member 15 are recessed as 15 designated by 18, said recesses providing pockets for the reception of short stems such as 19 that project from applicators 20. These applicators and their stems may be formed of any soft flexible material, such as cotton, wool, or any material that will function as a swab for applying the 20 rouge to the lips or face.

In some instances it may be found desirable to form the applicator from chamois skin or the like, with a filling of soft flexible material.

I prefer to construct the applicator that is used 25 for applying the facial rouge in the form of a flattened sphere and slightly larger in diameter than the applicator that is utilized for applying rouge to the lips.

The lip rouge applicator may be of any desired shape, although as illustrated in Fig. 2 I 30 prefer to form said applicator substantially conical in shape in order to give best results in use.

In the use of my improved compact, the button 35 17 is engaged by the thumb or finger and pushed in one direction or the other so as to correspondingly move member 15 and, such action brings one of the applicators into contact with the body of rouge contained in one of the caps. When one of the applicators is thus brought into contact with the corresponding one of the bodies of 40 rouge, the cap 14 containing said rouge is rotated first in one direction and then in the other so as to deposit a small amount of rouge on the surface of the applicator.

The cap containing the rouge is now removed 45 from body 10 and by means of pressure on button 17, the member 15 is moved outward to its limit of movement so that the rouge-carrying applicator will be projected into position where it may be conveniently manipulated in applying the 50 rouge to the lips or face.

The rouge used in the compact may be produced in small plug-like bodies and furnished to the purchasers of the compacts, thereby enabling 55 said bodies of rouge to be used as refills to replace

the bodies that have been exhausted or used up as a result of being transferred from the end caps to the lips and face.

If desired, one of the caps may contain a rouge applicable for use on both the lips and face and the other cap may contain a cosmetic applicable for use on the eyebrows after the manner of the generally used eyebrow pencil.

Thus it will be seen that I have provided a 10 lip and facial rouge compact that is relatively simple in construction, inexpensive of manufacture, and very effective in performing the functions for which it is intended.

It will be understood that minor changes in the 15 size, form and construction of the various parts of my improved lip and facial rouge compact, may be made and substituted for those herein shown and described, without departing from the spirit of my invention, the scope of which is set forth 20 in the appended claim.

I claim as my invention:

In a compact, a body, rouge containing caps removably positioned on the ends of said body, a member arranged to slide lengthwise through said body, applicators carried by the ends of said sliding member, which applicators are adapted to make contact with the rouge contained in said caps, one of which applicators is provided with a rounded outer face, the other applicator being substantially conical in shape, said body being 10 provided with a longitudinally disposed slot and a stud seated in the intermediate portion of said applicator carrying member, which stud projects through said slot to provide means whereby said applicator carrying member may be moved in 15 either direction to bring one of the applicators into contact with the rouge in the corresponding cap.

5
